L. ROSENWALD.
COLLAPSIBLE BOX.
APPLICATION FILED JULY 24, 1914.

1,168,563.

Patented Jan. 18, 1916.

UNITED STATES PATENT OFFICE.

LUCIAN ROSENWALD, OF KANSAS CITY, MISSOURI.

COLLAPSIBLE BOX.

1,168,563.

Specification of Letters Patent. Patented Jan. 18, 1916.

Application filed July 24, 1914. Serial No. 252,919.

To all whom it may concern:

Be it known that I, LUCIAN ROSENWALD, a citizen of the United States, residing at Kansas City, in the county of Jackson and State of Missouri, have invented a certain new and useful Improvement in Collapsible Boxes, of which the following is a specification.

My invention relates to improvements in collapsible boxes.

My invention is particularly adapted for use as a berry or fruit box.

The object of my invention is to provide a novel collapsible box, which may be cheaply manufactured, which is easily extended or collapsed, and which in the extended form will have great relative strength.

The novel features of my invention are 20 hereinafter fully described and claimed.

In the accompanying drawings, which illustrate the preferred embodiment of my invention, Figure 1 is a perspective view of my improved box, shown extended and 25 partly broken away. Fig. 2 is a plan view of the box in the collapsed form. Fig. 3 is an enlarged central cross section of the box in its extended form. Fig. 4 is an edge view of the box collapsed. Fig. 5 is a plan view 30 of the strip which forms the sides before it is formed. Fig. 6 is a plan view of the strip which forms the bottom before being formed. Fig. 7 is a perspective view of the inverted U-shaped brace. Fig. 8 is a top 35 view of the box, reduced, shown extended, a part of the removable bottom being broken away.

Similar characters of reference designate 40 similar parts in the different views. 1 designates a rectangular strip which forms the sides of the box, and composed of sheet wood, card board or other suitable material. The strip 1 is provided with 45 parallel transverse flexible joints 2 formed by increasing or scoring the strip at right angles to its longitudinal edges. The strip 1 is bent at the creases or joints 2 to form the shape of box desired, a rectangular box being shown, and the ends are overlapped and secured together, as shown in Figs. 1 and 8.

A second member or strip of rectangular 50 form and having a length about the same as the width of the box is provided with a middle rectangular portion 3, which forms the bottom of the box and which is con-

nected at opposite edges by parallel flexible joints 4 with two flaps 5 and 6, the upper ends of which are folded over and respectively secured to the outer sides of opposite 60 sides of the box, as shown in Figs. 1, 3, 4 and 8.

The bottom member or strip is provided with two parallel flexible joints 7 and 8 which extend obliquely from one longitudinal edge of the bottom member to the other longitudinal edge thereof, the angle of obliquity and the distance between the joints being dependent upon the dimensions of the box.

The joint 7 will in all cases have one end at the upper edge and one corner of the box, Fig. 1, and will extend downwardly obliquely across the flap 5. The disposition of both joints 7 and 8 is such that, when 75 the member or strip 1 is collapsed flatwise, Fig. 2, the bottom member will also be folded flatwise along the joints 7 and 8.

When the box is extended, as shown in Figs. 1, 3 and 8, the portion 3 will be disposed horizontally, and the flaps 5 and 6 will lie against the opposite inner sides respectively of the box. Preferably, the bottom portion 3 is disposed some little distance above the lower edge of the strip 1, 85 thereby leaving a space for berries or fruit, when the boxes are piled one on the other.

For holding the box securely extended, it may have placed in it a removable bottom member 9, having substantially the inner 90 dimensions of the box, and adapted to rest upon the bottom portion 3.

If desired additional means for holding the box extended may be provided in an inverted U shaped brace having a transverse 95 portion 10 adapted to be disposed just below, and against, if desired, the bottom portion 3. The said transverse portion 10 is approximately the distance between the sides of the box to which are secured the 100 flaps 5 and 6. Each arm 11 of the brace is preferably U shaped, and is adapted to embrace the adjacent side of the box, Fig. 3.

After the box has been extended, the brace is applied thereto, opposite sides of 105 the box being slipped into the U shaped arms, after which, the arms may be fastened to the sides by indenting them with a suitable punch or other instrument, not shown, thereby forming indentations 12 in 110 the arms and sides of the box, the indentations interlocking with the ones adjacent

thereto so as to prevent the brace slipping accidentally from the box.

When it is desired to collapse the box, the arms of each arm 11 may be sprung apart 5 sufficiently to permit of the removal of the brace. In collapsing the box, after the brace and bottom member 9 have been removed, the flap 5 is upwardly drawn at the same time the sides of the box are swung 10 lengthwise toward each other. When adjacent ends and sides are disposed parallel with each other, or substantially so, the bottom member will be folded flatwise along the creases 7 and 8, Fig. 2.

15 I do not limit my invention to the structure shown and described, as modifications, within the scope of the appended claims, may be made without departing from the spirit of my invention.

20 Having thus described my invention, what I claim and desire to secure by Letters Patent, is:—

1. A collapsible box having a plurality of sides flexibly connected at the corners so 25 as to collapse to flat form, and having a member located between the sides, said member having a bottom portion and two flaps respectively flexibly connected to opposite edges of the bottom portion and extending 30 upwardly therefrom and respectively secured to opposite sides of the box adjacent to the upper edges thereof, said member being provided transversely across with two parallel flexible joints extending obliquely 35 between opposite edges of said member, whereby said member may collapse to flat form when the sides are collapsed.

2. A collapsible box having a plurality of sides flexibly connected at the corners so 40 as to collapse to flat form, and having a member located between the sides above the lower edges thereof, said member having a bottom portion and two flaps respectively flexibly connected to opposite edges of the bottom portion and extending upwardly 45 therefrom and respectively secured to opposite sides of the box adjacent to the upper edges thereof, said member having two parallel flexible joints extending obliquely 50 between opposite edges and arranged to permit the member to collapse to flat form when the sides are collapsed.

3. A collapsible box having a plurality of sides flexibly connected at the corners so 55 as to collapse to flat form, and having a member located between the sides, said member having a bottom portion and two flaps respectively connected to opposite edges of 60 said portion and extending upwardly therefrom and respectively secured to opposite sides of the box adjacent to the upper edges

thereof, said member having two parallel flexible joints extending obliquely between opposite edges and arranged to permit the member to collapse when the sides are collapsed, and means adapted to extend between opposite sides of the box for holding said sides and member from collapsing. 65

4. A collapsible box comprising two rectangular strips disposed at right angles to each other, one strip having its ends secured to each other and provided with transverse flexible joints located at the corners of the box, so as to permit of the collapse to flat form of the strip, the other strip having 70 its opposite ends respectively secured to the opposing strip adjacent to the upper edge thereof and at opposite sides of the box and provided with two parallel transverse flexible joints disposed at equal distances from 75 the upper edge of the box. 80

5. A collapsible box comprising a rectangular strip having its ends secured to each other and provided with transverse flexible joints at the corners of the box, 85 the strip forming the sides of the box, and a second strip forming the bottom of the box and disposed at right angles to the first strip and having its ends secured to the other strip adjacent to the upper edge thereof and at opposite sides respectively of the box, the second strip having two transverse flexible joints disposed at equal distances 90 from the upper edge of the box and above 95 the lower edge thereof. 95

6. A collapsible box comprising a rectangular strip having its ends secured to each other and forming the sides of the box, and provided with transverse flexible joints at the corners of the box, and a second rectangular strip forming the bottom of the box and disposed at right angles to the first strip and having its ends secured to the other strip adjacent to the upper edge thereof and respectively to opposite sides of the 100 box, the second strip having two transverse flexible joints disposed parallel with each other at equal distances from the upper edge of the box, the second strip having two 105 parallel flexible joints extending obliquely between opposite edges of the second strip and arranged to permit the second strip to 110 collapse to flat form when the first strip is collapsed. 110

In testimony whereof I have signed my 115 name to this specification in presence of two subscribing witnesses.

LUCIAN ROSENWALD.
